UNITED STATES PATENT OFFICE.

PEDER O. PEDERSEN, OF FREDERIKSBERG, DENMARK, ASSIGNOR TO POULSEN WIRE-LESS CORPORATION, A CORPORATION OF ARIZONA.

ARC CONVERTER.

Original application filed June 21, 1919, Serial No. 305,844, and in Denmark March 4, 1919. Patent No. 1,544,102, dated June 30, 1925. Divided and this application filed December 1, 1923. Serial No. 677,965.

This invention relates to an arc converter for producing high frequency oscillations in an electric circuit, and more particularly to the so-called Poulsen arc.

5 The use of such arcs fed from a low frequency source to produce high frequency oscillations is now well-known; in such devices a magnetic blowout is provided for extinguishing the arc during each cycle of high 10 frequency, the oscillations being produced by the rapid variations in arc length and resistance.

15 This application is a division of a prior application filed in my name, entitled "Arc generators", having Serial No. 305,844, and filed June 21, 1919, Patent No. 1,544,102, dated June 30, 1925.

20 It is one of the objects of my invention to increase the stability of an arc converter of the Poulsen type.

In order to secure best results with an arc converter, the magnetic field that influences the arc should be just strong enough to blow out the arc once in each cycle. In case the 25 magnetic field be materially weaker than this desired value, the arc will have a tendency to travel too far along the electrodes and away from the edges; this results in a reduced efficiency owing to the existence of 30 an unnecessarily high arc voltage corresponding to this period, and furthermore the frequency of operation will also vary. But even with the most favorable value of the magnetic field to produce the desired extinction 35 voltage, there is a gradual increase in arc resistance following the comparatively gradual rise of the extinction voltage, so that the efficiency of the arc is limited.

40 It is another object of my invention to overcome this effect as much as possible, by ensuring that there be little variation in resistance from the time of drawing to the time of extinction of the arc. Stating it in another way, the object is to reform the 45 conditions of starting and blowing-out of the arc, whereby the arc resistance is reduced to a favorable minimum while the arc is burning. According to the invention this is accomplished by providing the cathode 50 with cooling or other means which limits the outward travel of the arc, and regulates the temperature at the starting point for a desired high starting voltage. It is also point-

ed out in this application how the electrodes may be formed, or arranged, or formed and arranged, relatively to each other, to augment this increase in efficiency, by reducing to favorable values, the increase in length and resistance of the arc during its period of burning in each cycle.

55 My invention possesses other advantageous features, some of which with the foregoing will be set forth at length in the following description, where I shall outline in full those forms of the invention which I have 60 selected for illustration in the drawings accompanying and forming part of the present specification. Although I have shown in the drawings only a few embodiments of my invention, I do not desire to be limited there- 65 to, since the invention as expressed in the claims may be embodied in other forms also.

70 Referring to the drawings:

Figure 1 shows for comparison the usual arrangement of the electrodes of an arc 75 converter;

Fig. 2 shows one embodiment of my invention; and

Fig. 3 shows a modification.

80 In the prior arrangements as illustrated in Fig. 1, the anode 1, which is shown as water cooled, is placed directly opposite a cathode 2. When the arc ignites it forms the path 3, and it is then gradually bowed out and increased in length until it is ex- 85 tinguished in the position 4. There is no limit placed on the travel of the arc, and it is possible that with a slightly inaccurate adjustment of the field, the arc may be ex- 90 tinguished only after it has been drawn out 95 to an undesirable extent.

In Fig. 2 such an occurrence is obviated, since there is a physical limit to the point of travel of the arc. This is accomplished by providing a cathode 5 having a cooling 95 back piece 6. This piece is formed of a poor electrical conductor, such as resistance carbon or a resistance metal having a high melting point. As soon as the arc strikes this back piece, a high resistance is introduced thereby into the circuit, the current through the arc decreases, and there is an attendant drop in the arc temperature, causing the arc to be extinguished. The back piece 6 may be joined to the cathode 5 or 100 not, as desired.

In this modification, therefore, there is a limit to the extent of arc length increase, and consequently the arc resistance is also limited, and maintained as near to its practicable lower limit as feasible, during the entire time of burning.

Substantially the same results may be obtained in other ways; for example in Fig. 3 there is shown an anode 7 of the usual form, 10 and a cathode 8, which is provided with a shoulder 9. This shoulder is made abrupt and fairly large in extent, so that the arc between the electrodes cannot extend further than the position shown at 9. The 15 length of cathode 8 is accordingly chosen to correspond substantially exactly with the desired travel of the arc, which is blown out at the hindmost edge or shoulder 9.

In both of the embodiments of Figs. 2 20 and 3, the cathode length must be determined with due regard to the limitation of the arc travel. The embodiments differ however in the mode of preventing the arc 25 from travelling further than defined by the cathode. In Fig. 2 this is accomplished by a cooling effect due to reduced current flow upon leaving the cathode; while in Fig. 3 the same effect is produced by so forming the cathode physically that it is substantially impossible for the arc to spread beyond a definite point.

I claim:

1. In an arc converter, a cathode having a length just equal to the most favorable 35 distance of travel of the arc along the cathode.

2. In an arc converter, a cathode, and a back piece for the cathode made from a material having materially poorer conducting properties than the cathode.

3. In an arc converter, a pair of electrodes between which an arc is to be formed, one of said electrodes having a length just equal to the most favorable distance of travel of the arc along the cathode.

4. In an arc converter, a pair of electrodes between which an arc is to be formed, and a back piece for one of said electrodes made from a material having materially poorer conducting properties than its associated electrode.

5. In an arc converter, a pair of electrodes between which the arc is formed, means for influencing the arc by a magnetic field, whereby the arc travels along the electrodes 55 between the time of drawing and extinction, and means for limiting the travel of the arc along the electrodes, comprising a resistance element disposed back of one of the electrodes and in the path of travel of the arc.

6. In an arc converter, a pair of electrodes between which the arc is formed, means for influencing the arc by a magnetic field, whereby the arc travels along the electrodes between the time of drawing and extinction, 65 and means whereby a resistance is introduced in the arc circuit upon travel of the arc beyond a definite limit.

In testimony whereof, I have hereunto set my hand.

PEDER O. PEDERSEN.
